UNITED STATES PATENT OFFICE.

JOHN V. GODDARD, OF TRENTHAM, ENGLAND, ASSIGNOR TO HUGH C. EDMISTON, OF NEW YORK, N. Y.

DESIGN FOR A COVERED DISH.

Application filed August 24, 1928. Serial No. 27,950. Term of patent 7 years.

To all whom it may concern:

Be it known, that I, JOHN V. GODDARD, a subject of the King of Great Britain, residing in Trentham, Staffordshire, England, have invented a new, original, and ornamental Design for Covered Dish, of which the following is a specification, reference being had to the accompanying drawings, forming a part hereof.

In the drawings, Figure 1 is a plan view, and Figure 2 is a view in side elevation of the article showing my new design.

I claim:

The ornamental design for a covered dish, substantially as shown.

This specification signed this 14th day of August A. D. 1928.

JOHN V. GODDARD.
